INCLOSED-ELECTRIC-ARC LAMP.

Specification of Letters Patent. Patented Jan. 13, 1914.

1,084,551.

Application filed December 5, 1910. Serial No. 595,720.

To all whom it may concern:

Be it known that I, MAX KÖRTING, a subject of the German Emperor, residing at 22 Bahnhofstrasse, Leutzsch, near Leipzig, Germany, have invented a new and useful Inclosed-Electric-Arc Lamp, of which the following is a specification.

Many arrangements have been proposed for the purpose of preventing deposit on the transparent globes of closed electric arc lamps, the electrodes of which emit vapors capable of producing a deposit on cooling.

This invention relates to closed electric arc lamps in which the depositing space or chamber is situated above the combustion chamber and in which the gases charged with the vapors pass out of the top of the combustion chamber and pass in again at the top of said chamber after passing through the depositing space. It has been found that in a lamp of this type the walls of the transparent portions of the lamp can be kept free from deposit even when the returning gases are still charged with considerable quantities of vapor if the walls of the combustion chamber are exposed directly to the major portion of the rays of the arc and the depositing space or chamber is adapted to cool the gases in an efficient manner or to such extent that when they re-enter the combustion chamber their temperature is considerably below that of the transparent portions of the lamp.

I have discovered that it is essential for the walls of the combustion chamber to be heated to a higher temperature than that of the returning cooled gases in order that no deposit may take place thereon. It is necessary for the walls of the combustion chamber to be exposed to the major portion of the rays of the arc in order that they may become sufficiently heated and therefore the combustion chamber is surrounded with an outer globe in order to prevent loss of heat.

One of the important advantages of this invention is that whereas usually it is sought to prevent deposit by so forming the depositing chamber that the returning gases should be as free as possible from vapors, this is unnecessary for even when the returning cooled gases contain considerable quantities of matter capable of deposition a deposit will not take place if the conditions hereinbefore set out have been observed.

The drawing shows an inclosed arc lamp

of the usual flame arc type containing mineralized electrodes.

1 designates a box containing the electrode-controlling mechanism which may be of any well known construction. A cap 2 covers this box and is provided with a pulley 3 by means of which the lamp may be suspended. A supporting plate 4 is suspended from the cap 2 by means of rods 5, pivoted to lugs 41 on the plate. This plate supports an outer casing or cylinder *d* having attached at its lower end a ring 6 which cooperates with a ring 7, the rings 6 and 7 being clamped together by means of bolts 8 and nuts 9. An end cap 10 provided with a ring 11 is supported from the ring 7 by means of a series of bolts 12 and nuts 13. The rings 7 and 11 support a cylinder or chimney *a* and a globe *b* both of which are transparent and the ring 7 also supports the reflector 14.

Electrodes *E* are supported in any suitable manner. A cylinder *c* is supported from the plate 4 and an inner cylinder *e* is also preferably provided to protect the upper electrode. The cylinders *d*, *c* and *e* form a plurality of annular passages which are connected at their upper ends by openings *c'* and which open at their lower ends into the upper end of the combustion chamber formed by the walls of the chimney *a*. The cylinders *d*, *c*, and *e* form a depositing device or chamber which is located above the combustion chamber and thus does not interfere with the distribution of the light from the arc and they serve to cool the vapors passing through them to a considerable extent below the temperature of the transparent chimney *a*. Heated gases pass upward through the space formed by the coaxial cylinders *c* and *e* out through the holes *c'* and down the space formed by the casing *d* from thence again into the top of the combustion chamber at a part nearer to the walls of the combustion chamber than the cylinder *c*.

The walls of the combustion chamber are exposed to the direct rays of the arc so that these walls are heated to a higher temperature than the entering gases or vapors whereby deposits on the walls are prevented. The provision of the globe *b* as well as the air space formed between the globe and chimney will prevent cooling of the chimney. The cooled gases entering the combustion chamber.

tion chamber while coming in contact with the walls thereof do not leave any deposit thereon.

I claim as my invention:

- 5 1. In an inclosed arc lamp the combination with a set of electrodes forming an arc, of a combustion chamber for the arc having transparent walls exposed to the direct rays of the arc and heated thereto to a relatively 10 high temperature, and a cooling chamber above the arc having a passage for leading the gases and vapors upwardly from the arc and a passage leading said gases and vapors downward to the combustion chamber close 15 to the heated walls thereof for returning the gases and vapors at a relatively low temperature to the combustion chamber, and a transparent casing inclosing the walls of the combustion chamber for conserving the heat 20 thereof to such an extent as to prevent deposits thereon.
2. In an inclosed arc lamp the combination with a set of electrodes forming an arc, of a cooling chamber above the arc adapted 25 to cool the gases arising therefrom, a combustion chamber into which the cooled gases pass downwardly from the cooling chamber and which has cylindrical transparent walls surrounding the arc in such proximity there- 30 to that a differential temperature in the cool- ing and combustion chambers is provided

whereby the gases arising from the arc are cooled and some deposit takes place in the cooling chamber while the walls of the combustion chamber by reason of their high 35 temperature are left free from deposits, and a transparent casing inclosing the walls of the combustion chamber and conserving the heat thereof to a degree above that of the gases and vapors entering from the cooling 40 chamber.

3. In an inclosed arc lamp, the combination with a set of electrodes forming an arc of a combustion chamber for the arc having transparent walls exposed to the direct rays 45 of the arc and heated thereby to a relatively high temperature, and a cooling chamber above the arc having a passage for leading the gases and vapors upwardly from the arc and a passage for leading said gases and vapors downward to the combustion chamber close to the heated walls thereof for returning the gases and vapors at a relatively low temperature to the combustion chamber, and a globe or transparent casing inclosing the 50 walls of the combustion chamber for conserving the heat thereof.

MAX KÖRTING.
